(57) **CLAIM**

The ornamental design for a display device with a graphical user interface having a responsive menu, as shown and described.

DESCRIPTION

FIG. 1 is a first view of the display device with a graphical user interface having a responsive menu.

FIG. 2 is a second view thereof.

FIG. 3 is a third view thereof.

FIG. 4 is a fourth view thereof.

FIG. 5 is a fifth view thereof.

FIG. 6 is a sixth view thereof.

FIG. 7 is a seventh view thereof; and,

FIG. 8 is a eighth view thereof.

The appearance of the transitional image transitions between the images shown in FIGS. 1, 2, 3, 4, 5, 6, 7, and 8. The progress period in which one image transitions to another image forms no part of the claimed design.

The dot-dash broken line(s) define the bounds of the claimed design and form no part thereof.

The broken line showing of the electronic device and display screen are for the purpose of illustrating environment and forms no part of the claimed design. The broken line showing of text and icons on the display screen forms no part of the claimed design.

1 Claim, 8 Drawing Sheets
